UNITED STATES PATENT OFFICE.

ROBERT S. HURLEY, OF TOLEDO, OHIO.

APPARATUS FOR HANDLING RAILWAY TIES.

Application filed June 18, 1923. Serial No. 645,947.

To all whom it may concern:

Be it known that I, ROBERT S. HURLEY, a citizen of the United States, residing at Toledo, in the county of Lucas and State of Ohio, have invented certain new and useful Improvements in Apparatus for Handling Railway Ties, of which the following is a specification.

This invention relates to an apparatus for handling railway ties, and constitutes part of a complete apparatus or system for picking up ties which are piled in ricks for seasoning in a storage field and transferring and loading them into small narrow gage trams, which trams are then run into treating cylinders wherein the ties are impregnated with creosote. In practice the tie ricks are about twelve to twenty feet high and forty feet long, and opposite one end of the ricks are standard gage tracks on which the ties are brought into the storage field, and opposite the other end of the ricks are the tram tracks; these tracks dividing the field into narrow yards. In some yards the standard gage tracks are equipped with a third rail to accommodate the narrow gage trams. The apparatus of the present invention is designed to facilitate and expedite the transfer of the ties from the ricks onto the ground adjacent to the tram car; whence, by the aid of another apparatus constituting the subject matter of a companion application filed December 24, 1923, Serial No. 682,372, the ties may then be loaded onto the trams.

In the accompanying drawings I have illustrated a practical and approved embodiment of my invention and referring thereto—

Figs. 1 and 2 are front and side elevations, respectively, of a tie rick, shown equipped with a portion of the apparatus for facilitating the removal of the ties one at a time from the rick; these views illustrating the manner in which the first five or six ties of each horizontal layer lying adjacent to the front of the rick are discharged manually;

Fig. 3 is a fragmentary top plan view of Fig. 1;

Fig. 4 is an enlarged fragmentary top plan view of Fig. 2, more particularly illustrating the structure of a teetering bar and

jigging bar at the front end of the trolley track;

Fig. 5 is a side elevation of the parts shown in Fig. 4, as viewed from the bottom 55 of the latter figure.

Fig. 6 is a front elevation of the upper portion of the rick, showing, in association with the trolley track and teetering and jigging bars an auxiliary teetering roller 60 and bar, and a trolley truck or carrier for lifting the remaining ties of the horizontal layer, swinging them horizontally through a right angle and transferring and delivering them to the auxiliary teetering roller and 65 bar;

Fig. 7 is a fragmentary top plan of the parts shown in Fig. 6, showing in full and dotted lines the position of the trolley when picking up and transporting a tie, respectively; 70

Fig. 8 is a fragmentary side elevation of the upper portion of a rick showing by full and dotted lines, respectively, positions of the trolley truck when transporting and 75 delivering a tie to the teetering roller;

Fig. 9 is an enlarged top plan view of the teetering and jigging bars and the auxiliary teetering roller and bar, as shown in Fig. 8;

Fig. 10 is a side elevation of the parts 80 shown in Fig. 9, viewed from the bottom of the latter figure;

Fig. 11 is a side elevation of the trolley track and truck; and

Fig. 12 is a vertical section, enlarged, of 85 the trolley truck taken on the line 12—12 of Fig. 11.

Referring to the drawings, 15 designates as an entirety a rick of ties; the manner in which they are piled up to secure ventilation and effect their drying out being clearly illustrated in Figs. 1 and 2. As previously stated, after the ties in the rick are thoroughly dried and ready for the creosoting treatment, they are unloaded from the rick from the top of the latter downwardly transferred to small tram cars and, on the latter, carried into the treating cylinders. The apparatus of the present invention is designed to facilitate the manual unloading of the ties one at a time from the rick and their delivery on end to a position adjacent to the 90 95 100

tram track, whence they may be loaded onto the tram car.

16 designates a trolley track, herein shown as consisting of a round rod or tube that is 5 inserted centrally between and transversely of the two spaced topmost horizontal rows of ties, and may be made in separably coupled sections if desired. Secured to the forward end of the track 16 by a T-coupling 10 17 (Figs. 4 and 9) is a teetering bar 18 formed with a tie-biting upper edge such as a series of upstanding teeth 19; and secured to one end of the teetering bar 18 by a T-coupling 20 is a forwardly extending 15 jigging bar 21 also equipped with a series of upstanding teeth 22 or other tie-biting upper edge. On the other end of the teetering bar 18 is a similar T-coupling 20', in the forward end of which is secured a short pipe 20 section 23. Fast on the pipe section 23 and the jigging bar 21 are a pair of depending hooks 24 (Fig. 5) formed with sharp prongs or teeth 25 which are driven into the side of the first underlying tie to anchor the trolley 25 track and jigging and teetering head in position. In the inner ends of the T-couplings 20 and 20' are secured short pipe sections 26 to which are fitted a pair of upstanding elbows 27 for a purpose hereinafter 30 closed.

It being understood that the ties as a rule are too heavy to be picked up bodily and carried by the average workman, the operation of the apparatus thus far described and illustrated in Figs. 1 to 5 inclusive is as follows. The workman on top of the rick grasps the foremost tie at one end and rolls it forwardly until it rests on the jigging bar 21, being held thereon 40 by the teeth 22. He then tilts the same upwardly, as shown by dotted lines in Fig. 1, and then, by rolling the tie in the opposite or rearward direction and at the same time swinging it angularly, transfers it from the 45 jigging bar 21 onto the teetering bar 18; this position being indicated by full lines in Figs. 1 and 2; the tie being then supported on the teeth 19 at an angle of approximately 45°. The operator then pushes 50 the upper end of the tie forwardly until the latter reaches approximately a vertical position, in which it is dislodged from the teeth of the teetering bar and drops end foremost onto the ground, usually falling 55 back into a leaning position against the face of the rick as shown in Figs. 1 and 2. From this position the tie is then transferred onto the tram by an apparatus not herein shown, but forming the subject matter 60 of the companion application hereinabove identified. The first five or six ties of the topmost layer are handled in this manner, being simply rolled over on the track 16 until they reach the jigging bar 21. The 65 removal of the first five or six ties affords

space for the subsequent use of the trolley truck in transferring the remaining ties of the layer to the teetering bar. When the trolley truck is used, however, the apparatus at the head of the trolley track is amplified by the addition thereto of an auxiliary teetering roll and bar shown in Figs. 6 to 10 inclusive. These parts may conveniently be constructed as follows. 28 designates a pair of hollow coupling members 70 mounted on the upper ends of vertical pipe sections 29 which are removably fitted into the upper ends of the elbows 27. Between and rigidly connecting and spacing the coupling members 28 is an auxiliary teetering 75 bar 30 having upstanding teeth 31. Connected into the rear ends of the coupling members 28 are a pair of short sections 32 onto which are fitted T-couplings 33 supporting a shaft 34 on which is mounted a smooth surfaced teetering roll 35. It is to be understood that the complete assembly last described is readily insertable into and removable from the upper ends of the elbow 80 couplings 27 as a unit; and this auxiliary 85 teetering mechanism is applied for use when the operator begins to use the trolley truck next described.

One simple and practical construction of this trolley truck is illustrated in detail in Figs. 11 and 12; one peculiarity thereof being its capacity for a considerable variety of tipping and turning movements required on account of the peculiar manipulation 90 of the tie in transferring it from its point of rest to its point of discharge from the top of the rick. In and between a pair of parallel horizontal truck bars 36 (Fig. 12) are journaled a pair of trolley wheels or rollers 37 preferably made with concave treads fitting the round track 16. Secured to the outer side of one of the truck bars 36 are a pair of depending guards 38 that 100 overlie one side of the track 16 and serve the purpose of preventing the wheels slipping off the track when the truck is tilted sidewise to pick up the tie as hereinafter described. Mounted in and between the side bars 36, centrally of the latter, is a shaft 39 on which is mounted a slotted block 40; and pivotally mounted at its lower end on the shaft 39 in the slot of the block 40 is an upstanding rod or stem 41. Surrounding the rod 41 and stepped at its lower end on the block 40 is a tubular member 42, rigidly mounted on the upper end of which is a horizontal head-piece 43; and welded or otherwise secured to the upper side of the member 43 is a tie grip 44 of substantially semi-circular form in cross section forming a pair of parallel lips having sharp edges 45 adapted to bite into the lower side of the tie as the latter is engaged by the head in the manner hereinafter described. Secured to one end of the member 43 is an 110 115 120 125 130

upstanding stem or shank 46, on the upper end of which is a horizontal operating handle 47. The central post or stem 41 extends through apertures in the members 43 and 44, and is headed over above the latter to lock the parts together with capacity for relative turning movement, as clearly shown in Fig. 12. By this construction the head-piece 43 and tie grip 44 are capable of turning or tilting in both horizontal and vertical planes.

The manner in which the ties are handled by the tool is progressively illustrated in Figs. 6, 7 and 8. The trolley is moved backwardly along the track until the next tie to be removed is reached. The trolley is then tilted downwardly sidewise on one side of the trolley track, as illustrated in Figs. 6 and 7, and the head-piece is entered beneath the tie. The handle is then swung to the vertical position, which lifts the tie onto the head-piece, as shown by dotted lines in Fig. 6, the sharp edges of the lips 44 biting into the tie and thus anchoring it on the trolley. After engaging the tie the operator proceeds toward the roller 35, one end of the tie dragging which automatically causes the tie to turn through the desired angle. The loaded trolley is then readily drawn along the track, as illustrated in Figs. 7 and 8, until it reaches the advanced position shown by full lines in Fig. 8; whereupon, by tilting the handle forwardly, the tie is further advanced and brought to rest on the roller 35 in the dotted line position shown in Fig. 8. The operator then lifts the rear end of the tie, rolls it over the roller 35 for a foot or two simultaneously tipping its forward end downwardly until it catches and is suspended on the teeth 31 of the auxiliary teetering bar 30. A slight further elevation of the rear end of the tie and a forward push on the same throws it clear of the teetering bar and the tie drops lower end foremost against the face of the rick in the manner already described.

In this way all the remaining ties of the top layer are unloaded from the rick. The spacing tie or ties at one side of each horizontal row, which are relatively few in number, are lifted at one end by hand and then swung through a right angle crosswise of the track, whereupon the trolley may be inserted thereunder and the tie transferred to the discharge point in the manner already described.

When one complete horizontal layer of ties has been thus removed, the track with its jiggling and teetering bar is shifted to a position beneath the next horizontal row of ties which has thus become the topmost layer; and the described operations are repeated. After the rick has been lowered to a point at which the forward end of the tie, when tilted on the teetering bars, strikes

the ground, the ties having been transferred by the trolley to the forward edge of the rick, they are then tilted forwardly and downwardly on the roller 35 and auxiliary bar 30 until their lower ends rest on the ground, and are then transferred one by one by the operator on the ground to the tram loading mechanism.

The described apparatus greatly facilitates and lessens the manual labor and strain of handling these heavy articles and transferring them from the tall ricks in which they are piled to a position favorable for their loading onto the tram cars; enabling the job to be easily, rapidly and comfortably performed. While the described invention has been designed primarily as an unloader, it may be used in the operation of stacking ties in connection with a hoist which will pull the tie out of the car and elevate it to the required height and deposit it on the edge of the pile, whence it will be picked up by the truck, carried back and deposited in place; its action in such case being simply the reverse of that herein described.

While I have herein shown and described one practical embodiment of the invention which has been found in practice to satisfactorily effectuate the purposes of the invention, it is manifest that the structural details may be widely varied and modified within the skill of the designer without involving any departure from the principle of the invention, or sacrificing any of the advantages thereof. Hence I reserve all such variations and modifications as fall within the spirit and purview of the appended claims.

I claim—

1. In an apparatus for unloading ties from ricks, the combination of a track insertable between the topmost and next underlying horizontal rows of ties, and a transversely disposed teetering bar on the forward end of said track.

2. In an apparatus for unloading ties from ricks, the combination of a track insertable between the topmost and next underlying rows of ties, and a transversely disposed teetering bar on the forward end of said track provided on its upper edge with means for biting into the tie.

3. In an apparatus for unloading ties from ricks, the combination of a track insertable between the topmost and next underlying rows of ties, a transversely disposed teetering bar on the forward end of said track, and means for anchoring said track and teetering bar in place.

4. In an apparatus for unloading ties from ricks, the combination of a track insertable between the topmost and next underlying horizontal rows of ties, a transversely disposed teetering bar on the forward end of

said track, and a pair of depending sharp pointed hooks connected to said teetering bar adapted to be driven into the face of the foremost underlying tie to anchor said teetering bar and track in place.

5. In an apparatus for unloading ties from ricks, the combination of a track insertable between the topmost and next underlying rows of ties, a transversely disposed teetering bar on the forward end of said track provided with upstanding teeth, and means for anchoring said track and teetering bar in place.

6. In an apparatus for unloading ties from ricks, the combination of a track insertable between the topmost and next underlying horizontal rows of ties, a transversely disposed teetering bar on the forward end of said track provided with upstanding teeth, and a pair of depending sharp pointed hooks connected to said teetering bar adapted to be driven into the face of the foremost underlying tie to anchor said teetering bar and track in place.

7. In an apparatus for unloading ties from ricks, the combination of a track insertable between the topmost and next underlying rows of ties, a transversely disposed teetering bar on the forward end of said track, and a forwardly extending jiggling bar on said teetering bar.

8. In an apparatus for unloading ties from ricks, the combination of a track insertable between the topmost and next underlying rows of ties, a transversely disposed teetering bar on the forward end of said track, and a forwardly extending jiggling bar on one end of said teetering bar disposed substantially at right angles to the latter.

9. In an apparatus for unloading ties from ricks, the combination of a track insertable between the topmost and next underlying rows of ties, a transversely disposed teetering bar on the forward end of said track, and a forwardly extending jiggling bar on one end of said teetering bar; said teetering and jiggling bars being equipped with upstanding teeth.

10. In an apparatus for unloading ties from ricks, the combination of a track insertable between the topmost and next underlying horizontal rows of ties, and a tie lifting and carrying trolley adapted to travel on said track and equipped with a handle for manual operation thereof.

11. In an apparatus for unloading ties from ricks, the combination of a track insertable between the topmost and next underlying horizontal rows of ties, a tie lifting and carrying trolley adapted to travel on said track and equipped with a handle for manual operation thereof, and a transversely disposed member on the forward end of said track for supporting and

teetering a tie in the operation of discharging the latter from the top of the rick.

12. In an apparatus for unloading ties from ricks, the combination of a track insertable between the topmost and next underlying horizontal rows of ties, a tie lifting and carrying trolley adapted to travel on said track and provided with a handle for manual operation thereof, and a transversely disposed teetering roll mounted on and above the forward end of said track.

13. In an apparatus for unloading ties from ricks, the combination of a track insertable between the topmost and next underlying horizontal rows of ties, a tie lifting and carrying trolley adapted to travel on said track and equipped with a handle for manual operation thereof, a transversely disposed teetering bar mounted on and above the forward end of said track and equipped with upstanding teeth, and a transversely disposed teetering roll in rear of said teetering bar.

14. In an apparatus for unloading ties from ricks, the combination of a track insertable between the topmost and next underlying horizontal rows of ties, a main teetering bar mounted on and transversely of the forward end of said track, an auxiliary teetering bar and teetering roll removably connected to and disposed above and in rear of said main teetering bar, and a tie lifting and carrying trolley adapted to travel on said track and equipped with a handle for manual operation thereof.

15. A trolley truck for use in removing railway ties from ricks, comprising a truck frame, wheels mounted tandem therein, a central upstanding support on said frame, a horizontal tie lifting and carrying member swiveled on said support, and an operating handle connected to said tie lifting and carrying member.

16. A trolley truck for use in removing railway ties from ricks, comprising a truck frame, wheels mounted tandem therein, a central upstanding support pivoted for fore and aft swinging movement on said frame, a horizontal tie lifting and carrying member swiveled on said support, and an operating handle connected to one end of said lifting and carrying member.

17. A trolley truck for use in removing railway ties from ricks, comprising a truck frame, wheels mounted tandem therein, a central upstanding support pivoted for fore and aft swinging movement on said frame, a horizontal tie lifting and carrying member swiveled on said support, and provided with a sharp upper edge adapted to bite into the under surface of a tie, and an operating handle connected to said lifting and carrying member.

18. A trolley truck for use in removing railway ties from ricks, comprising a truck

- frame, wheels mounted tandem therein, a central upstanding support pivoted for fore and aft swinging movement on said frame, a horizontal tie lifting and carrying member 5 swiveled on said support and provided on its upper side with a pair of parallel lips formed with sharp upper edges adapted to bite into the under surface of a tie, and an operating handle connected to one end of 10 said lifting and carrying member.
19. In an apparatus for removing railway ties from ricks, the combination with a track rail, of a tie lifting and carrying trolley mounted to travel on said track rail and 15 provided with flanged wheels engaging the latter; said trolley being capable of a lateral tipping movement on said track rail, and
- means mounted on said trolley and engaging with said track rail to prevent the trolley from slipping off said track rail when tilted laterally thereon. 20
20. In an apparatus for removing railway ties from ricks, the combination with a round track rail, of a tie lifting and carrying trolley mounted to travel on said track rail and provided with wheels having concave treads fitting said track rail, and guard strips attached to a side of said trolley and extending downwardly alongside said track rail to prevent derailment of said trolley 25 when the latter is tipped laterally on said track rail to engage beneath a tie. 30

ROBERT S. HURLEY.
